UNITED STATES PATENT OFFICE

GEORGE F. KUEHN, OF JACKSON HEIGHTS, NEW YORK, ASSIGNOR TO EISEMANN MAGNETO CORPORATION, OF NEW YORK, N. Y., A CORPORATION OF NEW YORK

MAGNETO BREAKER ADJUSTMENT

Application filed December 19, 1929. Serial No. 415,284.

This invention deals with a breaker mechanism for a magneto, its principal concern being with the provision for setting or for adjusting within set limits the point at which the break occurs in relation to the position of the armature with respect to the magnet poles. It provides a simplified arrangement of the parts which have to do with this setting and adjustment making it possible to have a permanent setting or a variable one, for rotation in either direction, and it simplifies the whole breaker assembly by giving to one part the double function of being the breaker housing and the breaker cam. The range of variation of the cam setting is considerable and many different settings are possible, thus making the operation of the magneto more efficient because of the ability to set the break point precisely.

20 In the accompanying drawings:

Figure 1 is a view in section of a magneto in which the inventive ideas here disclosed are embodied.

25 Figure 2 is a fragmentary view, partly schematic, showing the relation between the armature, the poles, the breaker cam and the breaker cam follower, together with the provision for setting the range of adjustment of the break point.

30 Figure 3 is a similar view but with the breaker mechanism shown in end elevation and the adjustment limiting devices shown in section.

35 Figure 4 is an end view of the member which serves as a housing for the breaker mechanism and has a cam surface for actuating the breaker.

40 Figure 5 is a side view of the same member with a part shown in section about on the line 5—5 of Figure 4.

45 Figures 6 to 10 inclusive are like fragmentary views of the construction by means of which either a fixed break point or the limits of variation of the break point are set, the several views showing different settings.

50 Figure 11 is a partial view in section through the armature core and the bottom of the casing, illustrating the use of a setting gage.

The magneto has a main part 15 forming the casing for the end of the armature that carries the coils 16 and for the large gear 17 that turns the distributor arm 18. The gear 17 is mounted on a spindle supported in a bearing 19 that is received in an opening in the upper part 20 of the casing section 15 within the loop of the magnet 21. The lower part of the main casing section 15 has a recess for a bearing 22 that supports one end of the armature spindle 23.

A second casing section 25 fits the rim of the open end of the main section 15 and is held thereto by screws 26. This second section has an opening 27 in an inward flange 65 that has a flat outer face at the rim of the opening, and against this face rests the distributor cap 28 held by screws 29. Below this relatively large opening is a smaller one 38 which receives a member that supports 70 the breaker housing and also a bearing for the end of the armature shaft. The latter extends through to the breaker housing where it carries the rotating parts of the breaker mechanism, as described more fully 75 hereinafter.

A conductive ring 31 mounted on an insulating body turning with the armature spindle and suitably connected electrically with the secondary coil of the armature, rotates in contact with a spring-pressed carbon brush 32 mounted in a laterally extending arm 33 of the distributor cap 28. The cap is of molded insulating material. This brush is conductively connected, through the 85 interior of the distributor cap 28, with a center inwardly extending brush 34 which is mounted in a central nipple 39 and bears against that part of a conductive piece 35 on the distributor arm that is on the axis of the fibre gear 17. The end of this conductive piece turns with the distributor arm in a circle such that it just clears the electrodes or terminal pieces 36 which are on the inner ends of the nipples 37 integral with the distributor 90 cap. These nipples are arranged in a circular series and register with the exterior bosses 38 on the cap which receive the ends of the cables leading to the spark plugs. In the interior of the nipples are suitable provi- 100

sions for connecting the cables electrically to the terminal pieces 36. The construction and advantages of this distributor part of the magneto are described more fully in my 5 application Serial No. 415,285 filed herewith.

In accordance with usual practice, the primary and secondary coils are connected in series, one forming a continuation of the other, and the other end of the primary coil 10 is connected to the armature casing as a ground. The other end of the secondary coil is connected to the slip ring 31 as shown, by reason of which the high tension current may flow to the distributor. The end of the secondary coil which is connected to the live end 15 of the primary is also connected with one side of a condenser, thus putting the primary coil and the condenser in parallel, and to one side of the breaker, the other sides of the condenser and breaker being grounded. 20

The breaker mechanism is at the end of the armature shaft and is held thereto by a long screw 80 which threads into a member 25 81 that is secured within an insulating sleeve 82 set in a counterbore in the tubular member 83. This member 83 forms that end of the armature shaft, being secured by means of a flange 84 at its inner end to the core 126 30 of the armature. The tubular member 83 carries the insulating hub 67 on which is the slip ring 31. The distributor driving gear 35 83 is mounted next to the hub on this tubular member and, so that it may turn with it, it is held by screws 86 extending into the flanged end 84 of this member. The outer end of this hollow member 83 is divergent and extends into and slightly beyond the bearing 86 which is held in a recess in the inner face 40 of a circular member 87 mounted in the opening 88 (mentioned above) in the casing section 25. This member 87 serves as the fixed base of the breaker housing.

A disc or plate 89, received in a recess in the outer face of the base 87, has a rearward tapered extension 90 lying in the divergent end of the hollow extension 83 but clearing the screw 80. The disc 89 forms the base for the rotating breaker parts and turns with the armature and with the screw 80 although 50 insulated from the latter by a sleeve 91 which serves also to maintain the spacing of the screw and the disc. A hollow boss 92 on the base disc 89 contains a spring pressed carbon brush 93 which bears against the face 55 of the circular fixed base 87. Also mounted on the disc 89 is a block 94, insulated therefrom by a collar 95 around the screw 96 which holds the block on the plate and by the sleeve 91, described above, together with 60 a sheet of insulating material between the adjacent face of the disc and the block. The enlarged head 97 on the end of the screw 80 rests in a recess in the outer face of this block and is held from turning relatively to 65 the block by a spanner piece 98 held to the

block and engaging the faces of the hexagonal head (see Figures 1 and 3). The screw 80 thus holds the block 94 and the base disc 89, which are held together by the screw 96, against the hollow shaft member 83 so 70 that all rotate with the armature. There is a running fit between the disc 89 and the fixed base member 87.

Extending through the block 94 transversely (Figure 3) is a screw 100 with a 75 locking nut 101. One end of this screw serves as the fixed breaker point 102, adjustable in position by threading the screw in or out of the block. The movable breaker point 103 is at the end of one arm 104 of a bell crank 80 having a circular recess at its pivot point enabling it to be set over a boss 105 on the base disc 89, thus giving a mounting providing for rocking on the disc. The other arm 106 of the lever has an end recess filled by a bearing piece 107 of fibrous material 85 for engaging cams, yet to be described, which press the arm inwardly, and thus rock the lever, twice in each revolution to separate the breaker points. A flat spring piece 108 is fixed to another boss 108^a on the breaker disc 89 and its free end bears on the pivotal part of the bell crank lever to hold it on the boss 105. There is also a curved leaf spring 109 which is fixed at one end to a lug on the block 94 and extends around the pivot of the bell crank breaker lever to the arm 106 thereof that carries the cam follower. The effect of this spring is to swing the arm 106 outwardly against the cams, thus pressing the breaker point 103 against the fixed point 102. The breaker points when in engagement complete a circuit from the center screw 80 to the magneto casing, thence to ground. This 95 is a primary circuit since the inner end of the screw 80 is connected to a terminal 80^a to which the live end of the primary coil is connected and the screw is otherwise insulated from the casing by the arrangement described. 100

The cams 110, 111 mentioned above for actuating the breaker are formed on opposite sides of the inner face of a ring member 112 (Figs. 1, 3, 4, 5) which is considerably wider than the cam faces and serves as a housing 115 surrounding the breaker mechanism just described. It extends into an annular recess 113 (Figure 1) in the outer face of the circular member 87. The outer end of this ring member 112 receives the breaker cap 115 which is a molded piece carrying a binding post 116 for the usual wire leading to a switch and thence to ground. Connected with the binding post inside the breaker cap is a spring contact 117 bearing against the enlarged head 120 97 of the screw 80. A screened opening 118 in the cap provides for venting the breaker chamber of any gases created by the breaker point arcing. 125

The cams 110, 111 are integral segmental 130

parts of the ring, being shaped by milling and grinding. The outer face of the part of the ring that extends into the base piece has a recess 120 that extends something less than a quarter way around the ring and is so cut that its bottom surface lies on a chord of the ring circle or, as shown here, on two nearly parallel but intersecting chords 121, 122. The bottom surface co-acts with screws 123, 124 (Figures 1, 2, 3, 6-10) extending into the recess from the under side through a part of the base member 87 that extends down through a slot in the casing 25 at the rim of the opening 88. The reason for this extension is that the material of the ring 87 is better suited to being tapped than the casing material, through which the tapped holes would extend were it not for this extension, as in Figure 2. The purpose of this is to determine the single position of the ring 112 if it is to be fixed or to determine the limits of its movement angularly if it is to be adjustable. Positions of the ring are considered in relation to the position of the armature at the time the cam follower first engages either cam and is moved thereby to separate the breaker contacts 102, 103. The point at which that separation occurs is the break point.

Since the cam follower 107 turns with the armature and has a definite position with respect thereto to bring the break point at approximately the right time, it follows that the position the armature core 126 occupies with respect to the poleshoes 125 at the moment that the break occurs depends on the position of the breaker cams 110, 111, and conversely, by moving the cam ring, the break point may be made to correspond to any given armature position. Likewise, since the distributor arm 18 turns in a geared relation to the armature and has a definite position corresponding to the armature position at any instant, the position of the breaker cams determines the relation between the break and the position of the distributor arm with respect to the electrodes 36. Thus there is a correlation between armature position, distributor arm position and break point, and shifting the cams causes the break point to occur at different times with relation to the swing of the armature core 126 past the poleshoes and the movement of the distributor terminal 72 past a given electrode. The current in the primary at any instant while the circuit is closed depends of course on the position of the armature coil, or in other words, of the core 126, in relation to the fixed poleshoes 125.

The fibre gear 17 carrying the distributor arm 18 makes one turn for every three revolutions of the armature and the latter makes one and a half turns for every engine rotation. This is the relation for a six cylinder, four cycle engine in which each cylinder fires every two revolutions. For other types of engine, the relation is different but this one

type will serve as an illustration. It is to be understood that the armature is so connected with the engine that the distributor terminal 72 registers with each electrode as the piston of the corresponding engine cylinder reaches a point usually toward the end of its compression stroke, at which ignition is most effective ordinarily. The ring 112 is so arranged that when at one limit of its range of variation or in its fixed setting, either cam 110 or cam 111 swings the lever 106 and causes a separation of the points 102, 103, or in other words, a break, at the instant when a piston is at this point in its stroke and the distributor arm is opposite the corresponding electrode. The cam ring is so set that this point, the point whereat the break occurs with the distributor directly opposite the electrode in question, is the one at which the primary current is at its maximum value. For this there is a definite armature position which is known beforehand. That is the point therefore of greatest spark efficiency. When the break occurs, a higher voltage is induced in the secondary and is conducted through the distributor to the engine.

If the ring be moved from this end position, the break occurs after the piston reaches the said point in its stroke and the spark is said to be retarded. If no change is desired in the time of break, the ring is fixed in position with the result that the break always occurs when the piston is at the same point. What this point shall be depends on the position in which the ring is fixed and preferably it is the point at which the maximum primary current occurs. The two cams 110, 111, diametrically opposite, are provided so that there will be a break for every 180° of armature rotation, that is to say, for every 60° of distributor arm rotation, the reduction effected by the gears 85 and 17 being in the ratio of 3 to 1. This assumes a six cylinder engine. Thus the break occurs as the distributor arm is passing an electrode, for the electrodes are 60° apart, and three cylinders are fired on every rotation of the engine crank-shaft.

The point at which to set the cam ring, so that the break will occur when the armature is in position to give a maximum primary current, may be readily ascertained. From the design of the armature it is known of course at what angular position of the armature this maximum current occurs and a gage G may be provided which can be inserted through an opening 61 in the bottom of the magneto casing 15 and placed against one pole 125 (see Figure 11). Then the armature is turned until the edge of one poleshoe 126 rests against the gage. The gage is of such size that it locates the armature in the position for maximum current. Holding the armature in that position, the

person making the adjustment may then set the cam ring accurately in a position such that the cam follower 107 of the breaker mechanism is at the end of the cam first engaged (see Figure 2). That insures a separation of the breaker points every time the armature reaches that position or one 180° from it, there being the two cams.

To provide for a similar setting when the magneto is to turn in the opposite direction, there is a similar opening 60 on the other side of the center line. These openings are normally covered by a screen 51 as they have a part in the ventilation of the magneto as described in my application Serial No. 415,283 filed herewith.

To provide what is in effect a micrometer adjustment, permitting very precise settings of the cam ring, there are two setting screws 123, 124 taking into the recess 120 in the ring 112 which carries the breaker cams 110, 111. There may be two tapped holes 130, 131 for these screws, as shown in Figure 2, but to give a greater range of settings, I provide five holes 130^{a, b, c, d, e}. The screws have either flat, rounded or tapered heads and different ones are most suitable for different positions of the ring, the object being to avoid having an engagement between locking surfaces 121, 122 and an edge of a screw. An engagement between flat surfaces is preferable.

In Figures 6 to 10 inclusive, are represented several different arrangements of the two screws. In these views the line denoted A indicates the line through the centers of the cams 110, 111 and the line B represents the line midway between the fixed poles and parallel to their faces. In Figure 6, the cam ring 112 is fixed in a position which, for counter-clockwise rotation of the armature, puts the line A 15° away from the center line B. This setting would be determined by use of the appropriate gage G as described above. The position of the ring can be set very precisely by slightly retracting one screw and advancing the other. When both screws engage the ring, further adjustment is impossible without moving the screws. It is the practice to seal over the tapped holes 130 so that a setting once made will not be changed by the unskilled user.

Figures 7, 8, 9 and 10 represent different settings which permit various ranges of adjustment effected by turning the ring manually. The screws are used in different holes, as will be noted by comparing Figures 6, 7 and 10, and in this way the desired differences in the permissive range of movement of the cam ring are obtained, the screws in each case having a practically flat surface engagement with the ring, thus insuring against cutting that would disturb the setting. In Figures 7, 8, 9 and 10 the timing ranges are successively greater, being re-

spectively 20° , 25° , 35° , and 40° . Not only are there variations in the extent of permissive movement, but there are differences in the limit positions as well, as indicated by the different angles between the lines A and B in the several views.

When the setting is such as to permit a limited movement of the ring, the ring is provided with an arm 135 to which a control lever may be connected (Figure 3). The arm has a split yoke 136 surrounding the cam ring 112 and clamped against it by a screw 137 connecting the two parts of the yoke. The range of permitted movement of the ring depends both on which holes the screws are in and the extent to which they are inserted. Various arrangements are possible, as will be obvious, and by proper selections many very precise settings may be had. The range of permissive movement may be limited to zero or to any desired finite amount.

In setting the screws for a desired range of adjustment, one screw preferably is set first to put one limit at a point such that the break will occur with the armature in position for maximum current. That setting is made with precision. Then the other limit may be set by simply moving the ring through an angle equal to the range desired and then setting another screw to prevent further movement. It is desirable to seal the holes 130 after such a setting, leaving the user the limited range of adjustment by means of the arm 135.

For opposite rotation, the settings are made in the same way but with the cam center line A on the opposite side of the line B and by using the gage G on the opposite side, that is, in the opening 60. The provision of more than two tapped holes for the limit screws makes possible this adaptation to either direction of rotation while enabling a great variety of precise settings for either direction of rotation.

The arrangement by which the member 112, which has the cams on its inner surface, serves as a ring housing for the breaker mechanism is of advantage not only for its simplicity and ease of adjustment but by reason of its mounting in a circular groove in the base member 87. This mounting affords an effective seal preventing the admission of dust and fines and similarly with the mounting of the breaker cap on the outer edge of the ring. The ring edges may be ground and in co-action with the surfaces of the cap and the base groove are very effective for the purpose.

Furthermore, it will be noted that the groove 120, into which the limiting screws 123, 124 extend, does not extend through the ring. There is for that reason no opening to the interior incident to the provision for adjustment as has been the case heretofore.

Those holes 130 that do not have screws in them, in any one setting, may be sealed over, although no considerable amount of the dust which might enter through them could pass 5 the seal afforded by the inner edge of the ring in engagement with the base of the recess in which the ring rests.

A further feature of great utility is the knurling on the exterior of the ring 112. 10 This ring is of hardened steel but the knurling is easily put on before the hardening. Then when an operating arm 135 is put on to permit the ring to be shifted, it is not necessary to provide interlocking parts on the part 15 of the arm surrounding the ring. An inexpensive die cast arm, of softer material than the ring, is provided and when tightened on the ring by the screw 137 becomes locked thereon due to the biting of the knurling into 20 the softer metal of the arm. Thus the arm is securely held from slipping about the ring.

I claim—

1. In a magneto, a casing, a rotatable breaker mechanism and a member mounted 25 on said casing to form a ring housing for said mechanism, said member having a cam on its inner surface for actuating said breaker mechanism and having a movement between limits to vary the point of actuation of the 30 breaker mechanism and means adjustable to change the limits of the movement of said member.

2. In a magneto, a casing, a rotatable breaker mechanism, a member mounted with 35 freedom for turning on said casing to form a ring housing around said mechanism, and a cam on the inner surface of said ring for actuating the breaker mechanism, said member being shiftable between limits to vary the 40 point of actuation of the breaker mechanism and means adjustable to vary the limits of movement of said member in either direction.

3. In a magneto, a casing, a rotatable breaker mechanism, a ring member mounted 45 on said casing around said mechanism with freedom for turning and a cam on the inner surface of said ring for actuating the breaker mechanism, together with a cap on the outer edge of said ring member, said ring member 50 being shiftable between limits to vary the point of actuation of the breaker mechanism and means adjustable to vary the limits of movement of said member.

4. In a magneto, a casing, a rotatable breaker mechanism, a ring member mounted 55 on said casing around said mechanism with freedom for turning, a cam on the inside of said ring for actuating said mechanism, and means for limiting the permissive angular movement of said ring member with respect 60 to the casing, said limiting means being adjustable to vary the limits of movement of said member.

5. In a magneto, a casing, a rotatable 65 breaker mechanism, a ring member mounted

on said casing around said mechanism with freedom for turning, a cam on the inside of said ring for actuating said mechanism, and screws in said casing adapted to engage said ring at spaced points to limit its permissive 70 angular movement with respect to the casing.

6. In a magneto, a casing, a rotatable breaker mechanism, a ring member mounted on said casing around said mechanism with freedom for turning, a cam on the inside of said ring for actuating said mechanism, said ring member having a flat portion on its outer side, and said casing having spaced screws 75 engaging said portion to limit the permissive angular movement of said ring member with 80 respect to the casing.

7. In a magneto, a casing, a rotatable breaker mechanism, a ring member mounted on said casing around said mechanism with freedom for turning, a cam on the inside of said ring for actuating said mechanism, said casing having three or more tapped holes 85 with screws in any two of them arranged to engage the ring member to limit its angular movement with respect to the casing.

8. In a magneto, a rotatable breaker mechanism, a cam member for actuating said mechanism on each rotation, said cam member being angularly adjustable about said mechanism, and a fixed casing having at 90 least three similar tapped holes with screws in any two of them arranged to engage said cam member to limit its angular movement, said holes being so arranged that, by putting the screws in different holes, different 100 timing ranges on fixed settings may be had.

9. In a magneto, a casing, a rotatable breaker mechanism, a circular recess in said casing, a shiftable ring member extending into said recess with one edge engaging the base thereof, said ring surrounding said breaker mechanism, and having a cap on its outer edge, whereby a sealed housing is provided for said breaker mechanism.

10. In a magneto, a casing, a rotatable breaker mechanism, a ring member mounted with freedom for turning on said casing but having a sealing engagement therewith, said member forming a housing around said breaker mechanism, a cam on the inner surface of said ring for actuating said mechanism, a cap for the outer end of said ring, and a groove in the outer face of said ring and extending part way around the ring, together with screws in said casing extending 110 into said groove to limit the permissive movement of said ring.

11. In a magneto, a casing, a rotatable breaker mechanism, a ring member mounted with freedom for turning on said casing and having a cam on its inner face for actuating said breaker mechanism, said ring having a knurled portion on its outer surface, together with an arm for shifting said ring, said arm having a portion surrounding said 125 130

ring and adapted to be tightened on said knurled portion, the part of said arm engaging the knurled portion being of softer material, for the purpose described.

5 12. In a magneto, a casing, a rotatable breaker mechanism, a closed ring member mounted on said casing around said mechanism with freedom for turning and a cam formed integral with said ring and projecting inwardly for actuating said breaker mechanism, said ring being recessed on its periphery for engagement with limiting stops.

15 13. In a magneto, a casing, a rotatable breaker mechanism, a closed ring member mounted on said casing around said mechanism with freedom for turning, a cam formed integral with said ring and projecting inwardly for actuating said breaker mechanism, said ring being recessed on its periphery for engagement with limiting stops and adjustable limiting stops for said ring.

25 14. In a magneto, a casing, a rotatable breaker mechanism, a closed ring member mounted on said casing around said mechanism with freedom for turning, a cam formed integral with said ring and projecting inwardly for actuating said breaker mechanism, said ring being recessed on its 30 periphery for engagement with limiting stops and limiting stops for said ring adjustable to effect independent variation of each limit of movement of said ring.

35 In testimony whereof I have signed my name to this specification.

GEORGE F. KUEHN.
